UNITED STATES PATENT OFFICE

JOSEPH FOLK, OF LA PORTE, INDIANA, ASSIGNOR TO U. S. SLICING MACHINE COMPANY, OF LA PORTE, INDIANA, A CORPORATION OF INDIANA

DEFLECTOR FOR SLICING MACHINES

Application filed April 13, 1927, Serial No. 183,391. Renewed October 23, 1929.

This invention relates to machines for slicing meat and other material in which the slices are severed by a rotary disc-shaped slicing knife, the slices being directed away from the knife by a deflector positioned adjacent the slicing edge.

One of the objects of the invention is to provide a deflector of improved construction and operation mounted for easy removal and replacement, the deflector being provided with a support which enables it to be replaced in the exact position of adjustment which it occupied prior to removal.

Other objects of the invention will appear from the following description.

The invention is exemplified in the combination and arrangement of parts shown in the accompanying drawings and described in the following specification, and it is more particularly pointed out in the appended claims.

In the drawings—

Fig. 1 is an elevation of a portion of a slicing machine knife showing one embodiment of the present invention applied thereto;

Fig. 2 is a top plan view of the mechanism shown in Fig. 1, with parts in section; and

Fig. 3 is a transverse section on line 3—3 of Fig. 2.

The numeral 10 designates a knife support or chain box of a slicing machine of well-known construction having a rotary disc slicing knife 11 journaled in a bearing 12 thereon. A bracket 13 is secured to the support 10 by cap screws 14 and carries a stud 15 projecting horizontally from the bracket 13, the axis of the stud being substantially parallel to the beveled portion 16 of the knife 11 at the point on the circumference of the knife directly opposite the stud 15. A slide block 17 is mounted on the stud 15 and is held in place thereon by a set screw 18. The block 17 is provided with a rectangular portion 19 having an outer bearing face 20. A deflector 21 is provided with a bearing face 22 for engaging the face 20 of the block 17 and is also provided with flanges 23 for engaging the side edges of the portion 19. The deflector 21 is secured to the block 17 by a

screw 24 having a collar 25 thereon disposed in a recess 26 in the bearing face 22 of the deflector. A knob 27 is secured to the end of the screw 24 for rotating the screw. It will be apparent that the collar 25 and knob 27 will hold the screw 24 to the deflector 21 so that it will not be accidentally lost or displaced when the deflector is removed from the block 17.

The deflector 21 is provided with a corrugated face having ribs 28 to reduce the frictional resistance to the movement of slices over the face of the deflector. The forward edge of the deflector is spaced backwardly a short distance from the cutting edge of the knife 11 so that after the slices are severed by the edge of the knife they are directed along the corrugations and deflected by the ribs 28 away from the knife. The relative position of the edge of the knife and the edge of the deflector may be adjusted by loosening the set screw 18 and shifting the deflector on its supporting stud 15. After the deflector has once been properly adjusted it is desirable that the adjustment shall not be disturbed so long as the edge of the knife is not materially changed by grinding. It is necessary, however, to remove the deflector from time to time for cleaning the deflector and knife. This may be done by removing the screw 24 from the block 17 which will permit the deflector to be removed from the block. The screw 24 will be retained in the deflector by the collar 25, as previously explained. After the parts have been cleaned the screw 24 is reinserted in the threaded opening in the block 17 and the flanges 23 will re-locate the deflector in the exact position it occupied prior to removal. If the edge of the knife should become worn the deflector can be readjusted on the stud 15, but readjustment of the block 17 is not necessary at the time that the deflector is removed for cleaning or other purposes.

It will be noted that the position of the stud 15 parallel to the beveled face of the knife 11 will permit adjustment of the deflector along the stud in a direction parallel to the bevel of the knife so that as the deflector is adjusted backwardly toward the

center of the knife, it will always bear against the beveled face of the knife at its outer edge.

I claim:—

1. The combination with a slicing knife, of a deflector for directing slices away from the knife, a support for said deflector adjustable in a plane substantially parallel to the plane of the edge of said knife to adjust said deflector along the edge portion of said knife toward and away from the cutting edge thereof, means for detachably securing said deflector to said support, and means for relocating said deflector on said support in a predetermined position relative thereto after removal of said deflector to permit cleaning. 70
2. The combination with a slicing knife having a beveled portion adjacent the edge thereof, a deflector disposed adjacent said beveled portion, means for supporting said deflector for adjustment toward and from the edge of said knife in the direction of said beveled portion, means for detachably securing said deflector to said supporting means, and means for relocating said deflector on said supporting means in a definite predetermined position thereon after removal of said deflector from said supporting means. 75
3. The combination with a slicing knife having a beveled portion adjacent the edge thereof, of a deflector for directing slices away from said knife, a support for said deflector, a bracket on which said support is adjustably mounted in a direction substantially parallel to the beveled portion of said knife, a threaded device for securing said deflector to said support, and means for retaining said threaded device on said deflector when said deflector is detached from said support. 80
4. The combination with a slicing knife, of a deflector for directing slices away from said knife, a support for said deflector having a threaded opening therein, a screw extending through said deflector and rotatable therein, said screw having a collar thereon disposed at one side of said deflector, and a finger-piece disposed at the opposite side of said deflector for facilitating rotation of said screw and for co-operating with said collar to hold said screw in position in said deflector. 85
5. The combination with a slicing machine knife having a beveled portion adjacent the edge thereof, of a deflector for directing slices away from said knife, a bracket having a stud projecting therefrom, a support adjustably mounted on said stud in a direction substantially parallel to the beveled portion of said knife, means for detachably securing said deflector to said support, and means for locating said deflector on said support in a definite position relative to each other. 90
6. The combination with a slicing knife having a beveled portion adjacent the edge thereof, a deflector having the edge thereof curved to conform to the edge of said knife 95
7. The combination with a slicing knife having a beveled portion adjacent the edge thereof, of a deflector having the edge thereof curved to conform to the curvature of the edge of said slicing knife and disposed adjacent said beveled portion, a support for said deflector, means for detachably securing said deflector to said support and locating said deflector on said support in a definite position relative thereto, said support having an opening therein, a stud arranged to enter said opening, said stud having the axis thereof substantially parallel to the beveled portion of said knife, and means for securing said support in different adjusted positions on said stud. 100
8. The combination with a slicing machine knife having a beveled portion adjacent the edge thereof, of a deflector having the edge thereof arranged to engage the beveled portion of said knife, a support for said deflector, a bracket on which said support is mounted for adjustment toward and from the edge of said knife in a direction substantially parallel to the beveled portion of said knife, means for holding said support in different adjusted positions, means for detachably securing said deflector to said support, and means for locating said deflector on said support in a definite position relative thereto while permitting ready removal of said deflector from said support. 105
9. A slicing machine comprising a rotatable knife, a deflector for deflecting slices away from said knife, a rigid support having a guide mounted thereon, a slide detachably mounted on said deflector and co-operating with said guide, said guide being adapted to guide said deflector along a predetermined path, and a pin for holding said slide and deflector in predetermined relationship with each other. 110
10. A slicing machine comprising a rotatable knife, a deflector for deflecting slices away from said knife, a rigid support having a guide mounted thereon, a slide detachably mounted on said deflector and co-operating with said guide, said guide being adapted to guide said deflector along a predetermined path by its co-operation with said slide, and a pin co-operating with means on said slide and deflector for positioning said slide and deflector in a predetermined position relatively to each other. 115
11. A slicing machine comprising a slicing knife, a deflector for directing slices away from said slicing knife, an adjustable support for said deflector, and a pin mounted on said deflector adapted to engage an opening in said support, said pin being constrained 120
12. A slicing machine comprising a slicing knife, a deflector for directing slices away from said slicing knife, an adjustable support for said deflector, and a pin mounted on said deflector adapted to engage an opening in said support, said pin being constrained 125

to move with said deflector and adapted to locate the deflector in a predetermined position on said support without disturbing the adjustment of said support.

5 In testimony whereof I have signed my name to this specification on this 31st day of March, A. D. 1927.

JOSEPH FOLK.
